UNITED STATES PATENT OFFICE.

ARTHUR H. SKAER, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE.

DRILL-STEEL RETAINER.

Application filed August 5, 1926. Serial No. 127,409.

The present invention has for its object the provision of a simple and effective means carried by a rotatable chuck for retaining a drill steel in the chuck, said means by reason 5 of its rotation with the chuck being thus relieved from a material amount of wear.

In the accompanying drawings:—

Figure 1 is a side elevation of an embodiment of the invention with the retainer in 10 its operative position,

Figure 2 is an end view thereof,

Figure 3 is a longitudinal sectional view 15 of the structure of Figures 1 and 2, but showing the retainer in its inoperative position,

Figure 4 is an end elevation of the mechanism as shown in Figure 3.

As shown, the drilling motor is designated 20 26, and the chuck 27. This chuck is rotatable in the barrel or cylinder of the motor by any suitable means. For example, the piston 26^a may have a rifle connection 26^b with the chuck, so that the two will rotate, the piston in turn being rotated by any means 25 well known in this art. The chuck, as shown, projects from the motor 26, and has an annular groove 28 in its projecting portion. In this groove 28 is rotatably engaged a collar 29 having a pivot and tie bolt 30, on which is pivotally mounted a link 31. The 30 link 31 is engaged with the larger end of a retaining link or loop 32, which consists of angularly disposed portions 33 and 34. The portion 33 has its internal space 35 sufficiently large to permit the passage there- 35 through not only of the drill steel, as 36, but also of the usual collar 37 of said drill steel. The portion 34 of the retaining link has the space 35^a therein of sufficient area to permit the passage of the steel 36, but is too small to 40 permit the passage of the collar 37, which will thus abut against said portion 34.

With this arrangement, it will be evident that if the drill is held in vertical position, the smaller portion 34 will ordinarily hang 45 down in the position illustrated in Figures 1 and 2, but the link can be moved to the position shown in Figures 3 and 4, so as to permit the introduction and removal of the

steel. When in the position illustrated in Figures 1 and 2, the steel is permitted to have 50 a certain amount of longitudinal movement, but it cannot become detached from the chuck 27, as the collar 37 will strike against the portion 34 of the link. Inasmuch as in the structure shown, the chuck and steel are 55 caused to rotate together, the mounting of the collar 29 on the chuck will insure that it, and consequently the steel retainer, will rotate with the chuck, so that there will not be 60 material wear between the parts.

From the foregoing, it is thought that the construction, operation and many advantages of the herein described invention will 65 be apparent to those skilled in the art, without further description, and it will be understood that various changes in the size, shape, proportion and minor details of construction may be resorted to without departing 70 from the spirit or sacrificing any of the advantages of the invention.

What I claim, is:

1. The combination with a drilling motor and a steel holding chuck rotatably mounted therein, of a steel retainer rotatably mounted on the chuck.

2. The combination with a drilling motor, of a steel holding chuck rotatably mounted therein and having a portion projecting therefrom, and a steel retainer movably mounted on the projecting portion of the 80 chuck.

3. The combination with a drill operating motor, of a steel holding chuck rotatably mounted therein and having a portion projecting therefrom, a collar rotatably mounted 85 on the projecting end of the chuck, a steel retaining loop having its internal space sufficiently large to permit the passage of a drill steel therethrough, a portion of such space being less than the diameter of the drill steel 90 collar and a portion greater than said collar, and a link connection between the loop and the collar that is mounted on the chuck.

In testimony whereof, I affix my signature.

ARTHUR H. SKAER.
